ELECTRICIAN'S COMBINED WIRE HOLDER AND HEAT ABSORBER, OR SIMILAR ARTICLE

Emanuel R. Archibald, 502 Buckeye St.,
Redwood City, Calif. 94063

Filed Jan. 15, 1971, Ser. No. 106,951

Term of patent 14 years

Int. Cl. D8—05

U.S. Cl. D8—71

FIG. 1 is a perspective view of an electrician's combined wire holder and heat absorber, or similar article, showing my new design;

FIGS. 2 and 3 are side and front elevational views, respectively, showing the central plunger depressed; and

FIG. 4 is a top plan view.

I claim:

The ornamental design for an electrician's combined wire holder and heat absorber, or similar article, substantially as shown and described.
